UNITED STATES PATENT OFFICE.

MASON HAIGH, OF CINCINNATI, OHIO.

PAPER-BAG MACHINE.

SPECIFICATION forming part of Letters Patent No. 726,528, dated April 28, 1903.

Application filed June 26, 1902. Serial No. 113,271. (No model.)

To all whom it may concern:

Be it known that I, MASON HAIGH, a citizen of the United States, residing at Cincinnati, in the county of Hamilton and State of Ohio, 5 have invented certain new and useful Improvements in Paper-Bag Machines, of which the following is a full, clear, and exact description, reference being had to the accompanying drawings, forming part of this specification.

My invention relates to machines for making paper bags, and more particularly to that class of machines which makes bags with side seams whose edges are turned over and pasted 15 to the opposite side of the bag in contradistinction to that class of machines known as "satchel-bottom" bag machines; and the object of my invention is to provide a simple, strong, and rapidly-running machine capable 20 of turning out large quantities of these envelop-shaped bags and which machine with slight alterations might be made to turn out ordinary envelops for mailing purposes.

The novelty of my invention will be herein- 25 after set forth, and specifically pointed out in the claims.

In the accompanying drawings, Figure 1, Sheet 1, is a side elevation of a machine embodying my invention. Fig. 2, Sheet 2, is an 30 end view of Fig. 1 looking toward the right. Fig. 3, Sheet 2, is an enlarged broken elevation of the finishing-cylinder and the gripping mechanism applied thereto. Fig. 4, Sheet 3, is an enlarged broken elevation of 35 the face of the finishing-cylinder and associated parts. Fig. 5, Sheet 3, is a diminished diagrammatic view of a portion of the web of paper, indicating the operations performed upon it as it passes through the machine. 40 Fig. 6, Sheet 3, is a perspective view of the completed bag as it comes from the machine.

The same letters of reference are used to indicate identical parts in all the figures.

Referring now to Figs. 1 and 2 and describ- 45 ing what is well known to the art in this class of machines, it is only necessary to say that A is any suitable and substantial framework, upon which is journaled a guide-roll B, over which the web of paper C from its roll D en- 50 ters the machine and first passes between a pair of printing-cylinders E, that print whatever is desired upon one or both surfaces of

the bag. The web of paper thence passes horizontally between a pair of slitting-rollers F, which divides the web longitudinally into 55 two equal parts, beginning at a, as seen in Fig. 5. From these rollers the divided web of the paper passes between cutting-rollers G, which cut out strips on both sides, as indicated by the dotted lines b of Fig. 5. From 60 the cutting-rollers G the divided web of paper passes between folding mechanism H of well-known construction in this class of machines which turns over that portion of the paper between the cut-out strips b and in line 65 therewith, as indicated at c in both Figs. 5 and 6. From this folding mechanism the web of paper passes between a pair of rolls I, which press down the folded side strips mentioned above.

All of the foregoing mechanism is old and well known to the art and needs no further description, and the machinery is driven by a common driving-shaft J, with belt-pulleys, fast and loose, K at one end, Fig. 2, with a 75 fly-wheel L on the opposite end, and with a series of connecting-gears M for all of the operating-shafts of the different rolls on one side of the machine, as clearly indicated in Fig. 2.

From the rolls I the paper passes downward and backward, as indicated by the arrow in Fig. 1, over the top of the finishing and gripping cylinder which forms the essential subject of my present invention. As it passes 85 under the bottom roll I and is received upon the finishing-cylinder N it is first caught by the gripping mechanism, (indicated at O, Fig. 1,) and thence passes to a series of pasting-wheels P, which are common to this class of 90 machines and which apply paste to the folded-over portions c, between the cut-out portions b. Thence the paper passes between the finishing-cylinder and a two-bladed creasing and cutting mechanism on a shaft R, Fig. 1, 95 that first makes a transverse crease on the dot-dash line e of Fig. 5, and then, as the paper passes through to a proper distance and the shaft R has made a half-revolution, severs the web, which severance may be a 100 straight line or may be angular from the center to each end after the manner of an envelop-flap, as desired. After creasing and before severance the divided web of paper is

carried from the creasing and cutting mechanism between the finishing-cylinder and a series of pressing-rollers S, Figs. 1 and 2, which press down the folded flaps at the edges and effect the pasting of the front to the back of the bag, and thereby complete the same.

Now, referring to Figs. 3 and 4, I will describe the mechanism by which the web of paper is gripped to the finishing-cylinder, is carried around the same and released therefrom. The finishing-cylinder N is preferably made of a size to turn out three complete bags at each revolution, and it therefore has three sets of gripping mechanisms, three creasing depressions, three cutting depressions, and three sets of gravity-pins for insuring the detachment of the cut edge of the bag from the finishing-cylinder before the bag passes between the finishing-cylinder and the pressing-rolls S. With a finishing-cylinder of this size there are accordingly three sets of these mechanisms, (a larger cylinder would require more,) and now I will proceed to describe the gripping mechanism. This mechanism is carried in transverse grooves on the face of the finishing-cylinder N and consists of two bars T, Fig. 4, each normally projected outwardly by coiled springs f at their ends beyond the edge of the cylinder and with their ends beveled to engage cams g, secured to the side of the frame A. Each of the bars T has upon it a pair of gripping-plates h, so located as to come over the outer edges of the severed web of the paper, their position being shown when they are not gripping the paper in Fig. 2 and by the dotted lines of Fig. 4, and their position being shown when over the edge of the paper to grip it by the solid lines of Fig. 4.

The before-mentioned action of the rods under the action of the cams g and springs f is simply to move them in and out. In addition to this movement the plates h, which grip the paper, have an action imparted to them by a shaft U with flingers V, Figs. 3 and 4, which, pivoted on the inner side of the finishing-cylinder, bear against the inner side of the bars T, with interposed springs j on studs k projecting inward from said bars, as seen in Figs. 3. The outer ends of the shafts U are provided with crank-arms W, Fig. 3, which ride on the underside of the cams g and throw out the gripping-arms h just at the point when the pasted bag has passed the rolls S, and thus release them from the finishing-cylinder, and they are permitted to drop in any suitable receptacle placed to receive them.

In addition to the gripping and releasing mechanism just before described I have provided gravity-pins X, projecting through the face of the finishing-cylinder adjacent to the cutting-slots l, which as the finishing-roller

descends and the web is severed are permitted to slip through the cylinder to insure the knocking off of the severed edge of the bag before the bag passes between the finishing-cylinder and the pressing-rolls S.

By the machine described I am enabled to turn out completed printed bags very rapidly and by very simple and efficient mechanism, the machine described being arranged to turn out six completed bags for each complete revolution of the finishing-cylinder N, the web of paper having been divided in two, so that when it reaches the finishing-cylinder two complete bags, side by side, are dropped off at the same time.

In Fig. 1 the creasing-blade h is shown as just entering the creasing depression m on the finishing-cylinder to crease the bags at their middles, while the severing-blade o will under the adjustment of the parts enter the severing depressions l to the right to sever the bags from the web, as will be readily understood.

Having thus fully described my invention, I claim—

1. In a paper-bag machine, the combination with folding and cutting mechanism, of a finishing-cylinder, transverse grooves in the periphery of said cylinder, transverse bars in said grooves, with their outer faces flush with the periphery of the cylinder, mechanism for actuating said bars longitudinally at predetermined distances in the travel of the cylinder, gripping-jaws carried by said bars, mechanism for actuating said bars to cause said jaws to grip and release the paper at predetermined times in the travel of said cylinder, creasing and severing grooves transversely arranged within the periphery of said cylinder, and creasing and severing mechanism for creasing and severing the bags transversely at predetermined times in the travel of said cylinder, substantially as described.

2. In a machine of the character described, the combination of the frame, the cams g, secured thereto, the finishing-cylinder N journaled between said cams, the recessed bars T arranged transversely of the periphery of the cylinder and actuated in one direction by one set of cam-surfaces, the gripping-jaws h carried by said bars, the levers V W, the former connected to the bars T and the latter actuated by the other set of cam-surfaces of the cams g, and the transverse creasing and severing depressions m l respectively, the creasing and severing blades n o carried by the shaft R, and the gravity-pins X, substantially as and for the purpose specified.

MASON HAIGH.
